CLAIM

I claim the ornamental design for a currency processing machine, as shown and described.

DESCRIPTION

FIG. 1 is a front view of an embodiment of a currency processing machine showing the new design;

FIG. 2 is a rear view thereof;

FIG. 3 is a left side view thereof;

FIG. 4 is a top plan view thereof;

FIG. 5 is a bottom view thereof;

FIG. 6 is an upper right front perspective view thereof; and, FIG. 7 is a lower left front perspective view thereof.

In each embodiment, a right side view is omitted because the right side view is symmetrical to the left side view.

The broken lines in the drawings illustrate subject matter that forms no part of the claimed design.
